Carlo P. Griffin
ATTORNEY.

UNITED STATES PATENT OFFICE.

LUTHER M. FLECKNER, OF SAN FRANCISCO, CALIFORNIA.

TREE-PROP.

1,376,686.

Specification of Letters Patent.

Patented May 3, 1921.

Application filed December 19, 1919. Serial No. 346,052.

To all whom it may concern:

Be it known that I, LUTHER M. FLECKNER, a citizen of the United States, residing at San Francisco, in the county of San Francisco, State of California, have invented a new and useful Tree-Prop, of which the following is a specification in such full and clear terms as will enable those skilled in the art to construct and use the same.

10 This invention relates to a tree prop and its object is to provide a support for a tree limb capable of being applied to any straight pole to produce the crotch for the tree limb. It will be understood by those skilled in 15 the art that large numbers of poles are used every year for the support of the limbs of fruit trees. These poles are usually selected tree limbs which have a natural crotch capable of holding the desired limb or else the 20 limbs must be tied to the prop.

In the present invention the crotch is secured to any straight pole or to any limb of the desired length and produces an artificial crotch for the support of loaded limb.

25 Another object of the invention is to produce a tie for connecting the crotch to the prop which is cheap to make and which can be secured to the crotch and the prop without the use of tools.

30 Another object of this invention is to provide a crotch for tree props which is capable of being moved up or down the pole supporting it by simply pushing the crotch toward the pole to lift the prong out of engagement with the pole.

35 Other objects of the invention will appear as the description proceeds.

An embodiment of the invention is shown in the drawing in which the same reference 40 numeral is applied to the same portion throughout, but I am aware that there may be modifications thereof.

Figure 1 is a view of the prop in use.

Fig. 2 is a plan view of the tie.

45 Fig. 3 is an enlarged perspective view of the tie and crotch separate from the prop, and

Fig. 4 is a perspective view of the crotch.

The numeral 1 indicates a tree prop 50 which has the tie 2 and crotch 3 connected thereto at one end.

The tie consists of a sheet metal stamping having a body 4 provided with double tabs 5 and 6 at top and bottom. At the sides the

body has a strap 7 and a strap 8 with a slot 9 therein. The slot 9 is wide enough to receive the strap 7 and when passed therethrough the strap is bent back and the tabs 10, 11 are bent down on the strap to hold it in place.

60 If the pole is small and the end of the strap 7 reaches the tabs 12, 13 they also may be bent down on the strap to hold its end down.

The crotch consists of a bent bar 14 provided with a point 15 at one end and it is secured to the tie by bending the double tabs 5 and 6 around the crotch.

When the crotch is to be used the strap is secured thereto and the strap is then bent 70 around the pole to be used as a prop. The strap 7 is then passed through the slot 9 and bent back upon itself, the crotch being placed inside the strap and the point 15 is pressed tightly into the pole. When the strap has 75 been pulled up tightly and bent back the tabs 10, 11 are bent down on it, and if the strap reaches the tabs 12, 13, they may also be bent down on the strap to hold it in place. The prop is then ready for use and 80 since the point 15 is pushed into the body of the pole it cannot slip down.

What I claim is as follows, but various modifications may be made in the construction shown in the drawings and above particularly described form, within the purview 85 of my invention:

1. A tree prop comprising a crotch, a metal clip having tabs for securing the crotch thereto, and a strap carried by the 90 clip adapted to pass entirely around a pole for securing the crotch thereto, said clip also having other tabs for securing the strap in position.

2. A tree prop comprising a crotch having 95 a prong to engage a pole, and a metal clip having tabs to secure the crotch thereto and also having a slot and a strap for securing the crotch to a pole.

3. A tree prop comprising a crotch having 100 a prong at one end, and a metal clip having tabs for securing the crotch thereto and also having a strap longer than the tabs adapted to pass around a pole and through a slot in the clip for securing the crotch to a pole. 105

In testimony whereof I have hereunto set my hand this 2nd day of December A. D. 1919.

LUTHER M. FLECKNER.
